UNITED STATES PATENT OFFICE

2,690,287

COVER LOCKING DEVICE FOR CONTAINERS

Frank G. Erskine, Kirkwood, and Paul Wasyluka,
St. Louis, Mo., assignors to Gaylord Container
Corporation, St. Louis, Mo., a corporation of
Maryland

Application January 2, 1951, Serial No. 203,959

3 Claims. (Cl. 229—45)

1

This invention appertains to a cover lock for a shipping container and more particularly to a cover lock for a receptacle of the class of multiple trip containers used to transport bottled and canned beverages.

The carrier hereinafter described may be constructed of solid fibreboard, corrugated fibreboard or any other suitable material.

Most containers for bottled beverages are of the double hinged cover type, each of the hinged cover panels being provided with depending marginal flanges on the free edges thereof. There is usually a slot in the upper edge of the end wall to receive the flanges depending from the lengthwise free edges of the cover panels. The slot is generally as deep as the depending flanges. This arrangement of the slot and the flange restrains any transverse movement of the cover panels relative to the container end wall. However, longitudinal and diagonal movement is not restrained by this arrangement which uses a full depth slot, that is, a slot whose depth is substantially the height of the cover flange. The container therefore has a marked tendency to flex and weave when moved, especially when horizontal forces are applied to the upper portion of the container.

In other containers having a modified arrangement, a slot which is the full depth of the cover flange is provided near each end of the flange depending from the longitudinal edge of each cover panel. In this style no slot is necessary in the upper edge of the end wall. Longitudinal movement of the cover panels relative to the container end wall is restrained, but transverse and diagonal movement is not limited. The container therefore is subject to transverse and diagonal flexing.

When the junction of the cover flanges and the end wall is either one of the full depth slots as above described, the container will be deficient in strength in at least one direction. This strength deficiency will cause the container to flex and weave when handled. Any flexing and weaving will cause the container to fail prematurely.

One of the primary objects of the present invention is to provide a coverlock for a hinged split cover container which will so strengthen and brace the container in all lateral directions as to substantially eliminate all weaving and flexing due to horizontal forces on the upper portion of the container.

Another object of the present invention is to provide a split cover container lock using only the material of the container.

2

A further object of this invention is to provide a hinged split cover lock easy and inexpensive to manufacture and which requires no special skill or special devices to assemble.

5 A still further object is to provide a cover lock for a container which is trim and neat in appearance.

Other objects and advantages of this invention will be apparent to those skilled in the art upon a full and complete understanding of the construction and operation of this device.

This invention comprises a hinged receptacle cover member provided with notches in interlocking engagement with opposing slots in the upper edges of the receptacle walls.

The invention also consists in the parts and in the arrangements and the combinations of parts hereinafter described and claimed. In the accompanying drawings which form part of this specification and wherein like numerals and symbols refer to like parts wherever they occur:

Fig. 1 is a plan view of a blank for a container embodying this invention.

Fig. 2 is a fragmentary perspective view of the container folded from the blank shown in Fig. 1 with the cover panel in partially closed position.

Fig. 3 is a fragmentary perspective view of the container with one cover panel closed.

Fig. 4 is a vertical cross-sectional view taken along the line 4—4 of Fig. 3.

Fig. 5 is an enlarged fragmentary plan view of the blank shown in Fig. 1 showing the cover locking device portion.

Fig. 6 is an enlarged fragmentary plan view of a blank for a container having a modified form of this cover locking device, and

Fig. 7 is a fragmentary perspective view of the modified form in assembled position.

Referring now to the drawings in detail it will be seen that the embodiment of the invention which has been illustrated is formed from the single blank shown in Fig. 1. This blank illustrates one common form of a multiple trip beverage case having bottom panels 1, side walls 2 and end walls 3. The upper edge of each end wall 3 is provided with a reinforcing flap 4 defined by a double score 5. Each reinforcing flap 4 is provided with a reinforcing strip 6 defined by the double score 7. The reinforcing strips 6 are provided with cover flange receiving slots 8. The reinforcing flaps 4 and the end walls 3 are provided with cover flange receiving slots 9 which register with said cover flange receiving slots 8 when the container is assembled. The receiving slots 9 are provided with tapered corners 10 to facilitate easy closing and locking of the cover

members. The end walls 3 are provided with handholes 11. Obviously, the handholes 11 are an optional feature of convenience which can be omitted.

The side walls 2 are provided with cover panels 12 defined by double scores 13. The free side edge of each cover panel 12 is provided with a depending flange 14 defined by a double score 15. Each depending side cover flange 14 is provided with a reinforcing strip 16 defined by a double score 17. The end edges of the cover panels 12 are provided with depending end cover flanges 18 defined by double scores 19. The depending end cover flanges 18 are also provided with reinforcing or end tabs 20 defined by an extension of the double score 15. The end tabs 20 are provided with a notch 21 having outer shoulders 22 and inner shoulders 23.

The container body is assembled in any suitable manner. A preferred form of assembling and fabricating the split covers and their depending flanges, with the included notch is as follows:

The end cover flanges 18 are folded along the double scores 19 to form an angle of approximately 90° with the cover panel 12. The end tabs 20 are folded along the extensions of the double scores 15 to form an angle of substantially 90° with the end cover flanges 18. The longitudinal or side cover flanges 14 are folded along the double score 15 to form an angle of substantially 90° with the cover panels 12. The reinforcing strips 16 are folded along the double scores 17, and around end tabs 20 and finally secured flatwise against the inner faces of the end tabs 20 and side cover flanges 14. Thus, the end tabs 20 are firmly held in between the side cover flanges 14 and the reinforcing strips 16. The box is now prepared for use.

With this arrangement, when one cover panel 12 is closed the end cover flanges 18 thereon are in flatwise contact with the outer surface of the upper portion of the end walls 3. The notch 21 fits into the slot formed by the registry of the receiving slots 8 and 9, the upper edge of the notch 21 abutting against the bottom of the slots 8 and 9. As shown in Fig. 4, an outer edge 22 of the notch 21 formed by the inside surface of the end cover flange 18 fits snugly against the outer surface of the end wall 3 below said slots. In a similar manner, an inner edge 23 of the notch 21 fits snugly against the reinforcing flaps 4 thereby preventing any longitudinal movement. In a like manner, the second cover panel 12 is brought into closed position. The side cover flanges 14 with reinforcing strips 16 thereon completely fill the slots 8 and 9 and restrain any transverse movement.

A modified form of the invention is illustrated in Figs. 6 and 7. In this embodiment, the end tab 20a is of uniform width throughout, but it is narrower than the end cover flange 18. The side cover flange 14a and the reinforcing strip 16a have cut out portions 24 having inner edges 25. The cut out portions 24 are in superimposed relation when the side cover flange 14a and the reinforcing strip 16a are in flatwise relation to each other with the end tab 20a positioned therebetween. In the assembled form a lower edge 26 of the end tab 20a will be even with the upper edges 27 of the cut out portions 24.

The operation of the modified form of the invention is similar to that of the preferred embodiment. When the cover panel 12 is closed, the inner edges 25 abut against the inner face of the end wall 3. Thus, in the second embodiment the abutting inner edges of the notch are formed in the side cover flange 14a and the reinforcing strip 16a thereby providing a three-ply surface for a portion of the upper edge of notch 21a whereas in the first embodiment, the upper edge of the notch 21 is only a single ply formed by the lower edge of the end tab 20.

The embodiments herein presented are illustrative and not restrictive; and the subject invention may be utilized in many forms by persons skilled in the art without departing from the invention.

What we claim is:

1. The combination of a cover member and an end wall with a slot therein wherein the cover member comprises a cover panel having a side cover flange and an end cover flange, said end cover flange having a connecting member thereon, said connecting member having an intermediate portion of less width than said end cover flange, said intermediate portion having a bottom edge, said side cover flange being provided with a cut out having an upper edge and an inner edge, said upper edge being in conterminous relation with the bottom edge of said intermediate portion, said connecting member being attached to said side cover flange thereby forming at least a two-ply assembly, said slot being of a depth substantially equal to the width of said intermediate portion of said connecting member, said intermediate portion being disposed through said slot in right angular relation to said end wall, said inner edge of said cut out being in edgewise abutting relation to the inner face of said end wall below said slot, the lower margin of said end cover flange extending below the level of said slot and being in flatwise contacting relation with the upper margin of the outer face of said end wall, said assembly of at least two-ply being positioned in said slot with the bottom edge of said intermediate portion of said connecting member and the upper edge of said cut out abutting against a portion of the end wall which forms the bottom of said slot.
2. The combination of a cover member and an end wall with a slot therein wherein the cover member comprises a cover panel having a side cover flange and an end cover flange, said end cover flange having a connecting member thereon, said connecting member having an intermediate portion of less width than said end cover flange, said intermediate portion having a bottom edge, said side cover flange having a reinforcing strip thereon, said side cover flange and said reinforcing strip each being provided with a cut out having an upper edge and an inner edge, said upper edges being in conterminous relation with the bottom edge of said intermediate portion, said connecting member being positioned between said side cover flange and said reinforcing strip forming a three-ply assembly, said slot being of a depth substantially equal to the width of said intermediate portion of said connecting member, said intermediate portion being disposed through said slot in right angular relation to said end wall, said inner edges of said cut outs being in edgewise abutting relation to the inner face of said end wall below said slot, the lower margin of said end cover flange extending below the level of said slot and being in flatwise contacting relation with the upper margin of the outer face of said end wall, said three-ply assembly being positioned in said slot with the bottom edge of said intermediate portion of said connecting member and the upper edges of said cut outs abutting

against a portion of the end wall which forms the bottom of said slot.

3. The combination of a rectangular paper-board box and a pair of cover members therefor hinged to the opposite sides thereof, each end wall of said box having a medial slot in the upper edge thereof, each cover member comprising a cover panel having a side cover flange and an end cover flange of like width, said side cover flange being folded back on itself to form a two-ply flange, the upper edge of the end wall having its edge folded upon itself to form a thickened wall portion of at least two plies, said end cover flange having a member connecting the adjacent ends of said side and end cover flanges thereby forming a cover flange junction, a notch formed in the lower edge of the cover flange junction, the outer edge of said notch being substantially in the plane of the outer face of the thickened end wall portion and the inner edge of said notch, 15

5 being substantially in the plane of the inner face of the thickened end wall portion, said slot in said end wall being of a depth substantially equal to the width of the cover flange minus the depth of the notch, the lower margin of said end cover flange extending below the level of said slot when the cover is in closed position and the notch and slot are in interlocking engagement whereby the end walls are locked against inward and outward movement. 10
